UNITED STATES PATENT OFFICE.

SAMUEL GREENHOUSE, OF AKRON, OHIO.

BOTTLE-FILLING MACHINE.

Application filed May 15, 1922. Serial No. 560,876.

This invention relates to new and useful improvements in bottle filling machines and has particular relation to a machine adapted to fill bottles with carbonated beverages.

5 Broadly stated, objects of the invention are to provide a bottling machine of simple, durable construction, which may be employed in bottling carbonated liquids with a minimum loss of gas with which the liquid is charged 10 and to thereby provide means whereby beverages containing a relatively large volume of gas may be produced at a low cost.

The invention includes new and efficient means for connecting a liquid supply tank to 15 bottles to be filled, improved means for maintaining a liquid at a certain level in said tank and novel means for providing for automatically limiting fluid pressure in the supply tank, and also includes certain new and novel 20 combinations of such means with ordinary means hereinafter described and set forth in the appended claims.

Inasmuch as my invention is particularly directed to improvements in certain devices 25 utilized in bottle filling machines, such as shown in Patent No. 956,285, it is not believed necessary to give a complete description of the machine nor to illustrate an entire assembly thereof. Only such parts will be shown and 30 described as are necessary for an understanding of the particular improvements apprehended by my invention.

In bottle filling machines of the type disclosed in the above mentioned patent, it has 35 been customary to utilize filling tubes, which communicate with the bottles to be filled and a liquid supply tank. These tubes are relatively light in construction and are usually directly connected to the machine by means 40 of a threaded surface provided on the exterior of the tube, which is adapted to be screwed into an opening provided adjacent the bottom of the supply tank.

It has been further suggested that bottle 45 sealing devices, slidably mounted upon the filling tubes and arranged to be raised and lowered each time a bottle is filled, be utilized in conjunction therewith, and although this affords satisfactory operating conditions, 50 nevertheless difficulty has been experienced by reason of the filling tubes becoming broken, usually at the point of connection with the machine. The tubes are broken mainly by reason of the bottle sealing device being permitted to drop upon the end of the tube as a

bottle has been filled, and such continued shocks or jars communicated to the tube cause it to be broken. Obviously, it is difficult to remove the broken ends to permit of replacement.

One of the primary objects of my invention is to provide a more durable structure to carry the bottle filling tube, which, in addition to extending the life of the tube, also functions to facilitate the filling of a bottle by providing a chamber into which air may escape from the bottle being filled as such air is displaced by a liquid.

Another object of the invention is to provide efficient means for controlling or limiting fluid pressure in the liquid supply tank. Ordinarily, bottle filling machines are connected through reducing valves to a carbonator, from which charged water is supplied at a lower pressure than that maintained in the carbonator. I have found that an advantage may be gained by disposing of such pressure reducing apparatus and by connecting the carbonator directly to the supply tank of the machine, a pressure regulator being utilized to limit the fluid pressure within the tank. The pressure may be regulated in the tank to any desired amount by suitably adjusting the pressure controlling apparatus of my invention.

In using the ordinary bottling machines and in following the known methods of bottling, the liquid becomes heavily charged with air. In practically all brewed or carbonated beverages there is a relatively large percentage of vegetable matter which, when confined in the presence of this free air, will soon lose its flavor and can be preserved but a short time. The presence of the air in the bottled liquid also gives the beverage a sharp unpleasant taste and the known methods and means employed wastes a large percentage of the carbonating gas with which the liquid is charged.

An important object of the invention is to provide a bottle filling machine which will deaerate the liquid without removing any substantial amount of the gas and to provide means whereby a relatively large percentage of gas may be maintained in the liquid with little or no loss and to provide means whereby bottled beverages may be greatly improved in flavor and may be preserved a relatively longer length of time.

A further object of the invention is to provide means and method for receiving the

liquid within the filling chamber directly from the gas charging chamber without the use of a pressure reducer and to provide means for permitting a constant escape of air from the upper portion of the chamber so that the free air is eliminated from the liquid in the chamber without removing the gas content therefrom and in consequence to provide means and method for producing a greater amount of highly carbonated beverages from a given amount of gas.

The invention also contemplates utilizing a particular type of valve for controlling the flow of liquid to the supply tank of the machine, which operates to effectively maintain a certain predetermined level of liquid in the supply tank.

Other and ancillary objects will become apparent from the following description of the drawings, in which like numerals indicate like parts, and further indicated in the appended claims.

In the drawings:

Figure 1 is an elevation of a filling tube connected to a cylindrical member which is constructed in accordance with my invention.

Figure 2 is a transverse sectional view of the device shown in Figure 1.

Figure 3 is a sectional view similar to Figure 2 of the parts shown in the relation occupied when a bottle to be filled is operatively disposed in communication therewith.

Figure 4 is a plan view of an end closing member utilized in the construction of the cylindrical member illustrated in the previous figures.

Figure 5 is a sectional view taken substantially along the lines 5—5 of Figure 4.

Figure 6 is a transverse sectional view taken substantially along the lines 6—6 of Figure 3.

Figure 7 is a partial assembly view of a bottle filling machine, partially in elevation and partially in section, illustrating the disposition of the device comprehended by my invention.

Figure 8 is a sectional view of a pressure limiting device, which is adapted to be connected to the fluid supply tank of the machine.

Figure 9 is a sectional view of a ball float valve which is adapted to control the flow of liquid to the supply tank of the machine, and,

Figure 10 is a sectional view of another end closing member utilized in the construction of the cylindrical member aforementioned.

In practicing my invention, I provide means for connecting a filling tube to the bottle filling machine which includes a plurality of tubular members connected in telescoping relation by means of an end closing member of frusto-conical shape, which is in-

teriorly threaded to receive the externally threaded portion of the filling tube and is provided with vertical passages adapted to provide fluid passages about the filling tube. A gasket formed of a suitable yieldable material is disposed within the outer tubular member and in engagement with the frusto-conical end closing member to thereby prevent escape of fluid from the passages when in operation. The opposite end of the cylindrical member is closed by means of another frusto-conical end closing member that is internally threaded for securement purposes and is provided with vertical passages to provide for the passage of fluid about the filling tube when it is disposed therein.

My invention further contemplates the provision of a fluid pressure control valve, which is formed of a tubular member having a restricted end portion which is exteriorly threaded for securement purposes and has a valve seat formed integrally with the tube adjacent the restricted end portion. The tube is also provided with openings in its body portion which constitute outlet passages for fluid under greater pressure than it is desired to maintain. A valve stem having a valve head is mounted within the tube with the valve head seated upon the valve seat. The head is maintained in such position by means of a spring enclosing the valve stem and engaging the valve head, and an end closing member adapted to be screwed into the tube.

A better understanding of the various devices comprehended by my invention and their operation may be had by reference to the drawings, in Figure 7 of which an assembly view of such portions of the bottling machine is set forth as will enable a description of the operation of the devices of my invention. As here shown, the bottle filling machine includes a supply tank 1 which is provided with a removable head 2 clamped in place by means of a plurality of bolts and wing nuts 3. The tank is connected to a suitable air or gas compressor, (not shown) by means of a conduit 4 connected through a main conduit 5 to the tank 1. Another conduit 6 connects the tank 1 to a supply of carbonated water, the flow of which is regulated by a float operated valve 7 mounted within the tank 1 upon the conduit 6.

The construction of the valve is clearly shown in Figure 9 and constitutes a semi-spherical body portion 8 having an inlet 9 and an elongate neck 10 formed with a U-shaped projection 11. A plurality of openings 12 afford outlets for liquid admitted to the inlet 9, and the neck 10 is closed by a suitable cap 13. A stem 14, having a removable valve head 15, operates in the neck 10, and is actuated by means of a ball float 16 attached thereto by a lever arm 17 pivoted upon the U-shaped projection, as indicated at 18, and

pivots connected to the stem at 19. The operation of the above described valve is obvious, inasmuch as the weight of the float 16 is sufficient, when not counterbalanced, to lift the stem 14 to remove the head 15 from its seat over the inlet opening and permit free passage of fluid to the interior of the valve and through the openings 12 to the chamber in which it is mounted. The liquid gradually 10 raises the float and forces the stem 14 downwardly to close the opening when the liquid reaches a predetermined level.

The stem 14 extends upwardly into the cylindrical cavity in the neck 10 and terminates in spaced relation to the upper end thereof thereby forming a pressure chamber 10^a in the upper end of said neck. The stem 14 is provided with a bore 14^a which extends coaxially therethrough and provides a communicating passage between said pressure chamber 10^a and the cavity of the inlet 9, the cavity of the inlet 9 being filled with liquid under heavy pressure which will force the liquid through the bore 14^a in the stem 14 and 20 fill the pressure chamber in the upper end of the neck 10 thereby providing a counter pressure on the upper end of the stem 14 which will provide for greater ease and regularity of operation and will prevent a sudden opening of said valve.

The tank 1 is provided with a hand opening 20 suitably covered, as indicated at 21, which affords ready means for connecting a pressure limiting valve 22, through a conduit 23, 30 to the interior of the tank 1. A gauge 24 is mounted upon the conduit 23 to indicate the amount of pressure existing in the tank. For a clear understanding of the construction of the valve 22 reference may be had to Figure 8. 40 As here shown, the valve 22 comprises a tubular body 25 having a restricted end portion 26 exteriorly threaded, as indicated at 27. A valve seat 28 is integrally formed on the interior of the tube adjacent the restricted end 45 portion, and is adapted to seat a valve head 29 mounted upon a valve stem 30. The tube 25 is provided with a plurality of openings 31 in its body portion, which constitutes outlets for objectional gas and air. The end of the 50 tube is closed by a cap 32 having an opening 33 through which the valve stem 30 extends and is thereby maintained centrally located. In order to provide a pressure against the valve head 29, a spring 34 is disposed about 55 the stem 30 and engages the valve head 29 and the cap 32, which latter member is adjusted to various positions to regulate the degree of pressure necessary to raise the valve head 29 from its seat and permit of the escape of 60 trapped gas. In using my improved device, the valve 22 is adjusted to operate at the pressure required within the tank, the continued operation of the machine causes air and gas to constantly escape from the liquid within 65 the filling chamber so that the air and lighter

gases are constantly escaping through the valve 22. Inasmuch as the valve 22 is in constant operation, the volume of air or gases passing through the valve 22 is relatively small causing no disturbance in the tank, the gas being heavier than the air forms in a strata just above the liquid and is easily forced into the liquid by the pressure within the tank to replace the air and lighter gas, thus eliminated therefrom.

The fluid pressure in the upper part of the tank is usually lower than the pressure of the charged water in the carbonater and after the water has been admitted to the tank a certain amount of the gases with which it is charged escapes into the tank. While the amount of gas thus escaping is relatively small, the escape is continual and the upper part of the tank becomes filled with carbonic-acid gas. Water charged with carbon dioxide by the ordinary charging machines contains air and other objectional gases and such objectional gases being lighter than the carbon dioxide will rise to the top of the tank and be automatically discharged by the valve 22.

It will thus be seen that after the machine is in operation a short period of time the valve 4^a may be closed to shut off the pressure of air to the upper part of the tank. This invention thus provides means whereby a beverage may be produced having a relatively large volume of carbonic-acid gas and from which the objectional gases have been excluded and consequently provides a pleasant tasting, wholesome product.

A plurality of pipes 35 and 36 are mounted within the tank in communication with a valve 37, which is of well known construction and is provided with suitable openings to connect the pipes to respective openings 38 and 39 as an operating lever 40 is actuated by additional means that it is not believed necessary to show or describe. It suffices to point out that the valve is operated to various positions to first admit air or gas to the tube 35 to a bottle 41 positioned in engagement with a sealing device 42, which is moved upwardly into engagement with the cylindrical member 43. Obviously, since the pressure ordinarily maintained in the supply tank 1 is above atmospheric, it is necessary to equalize the pressure in the tank and in the bottle to obtain a flow of liquid from the tank to the bottle to be filled. Liquid is permitted to flow through an opening 44 in the bottom of the tank through a suitable opening in the valve 37, and thence to a filling tube 45 carried by the member 43. As the liquid flows from the tank into the bottle, the air in the bottle is forced upwardly through a suitable opening in the key 37 and through the tube 36 into the upper part of the chamber of the tank 1. The tube 36 is of ordinary construction and is provided at the top thereof with an ordinary weighted check

valve which will permit air or gas to flow into the tank, but which will not permit gas or air to escape therefrom.

The construction of the member 43 is clearly shown in Figure 3 and embodies a plurality of telescoping tubes 46 and 47, the interior one of which is threaded into a frustoconical end closing member 48. The member 48 is shouldered to engage the exterior tube 47, and a gasket 49 is disposed about the member 48 within the tube 47. A flanged nut 50 is adapted to be fitted within the tube 47 to compress the gasket 49 and provide a liquid seal between the member 43 and the sealing device 42. The member 48 is shown in cross-section in Figure 10, and, as will be seen from an inspection of this figure, is interiorly threaded to receive the threaded filling tube 45. Vertical grooves 51 afford passages around the tube 45 when it is fitted within the member. The opposite end of the device 43 has annular washers 52 mounted to close the space between the telescoping tubes, and upon which the flanged frustoconical end closing member 53 is mounted with its cone extending towards the interior of the tube.

The construction of the member 53 is illustrated in Figures 4, 5 and 6, and is similar to the end closing member 48 in that it is provided with vertical grooves 54, as well as screw threads, to receive the threaded end of the tube 45. The exterior surface of the free end of the member 43 is threaded, as indicated at 55, to afford means for attachment to the tank 1.

From the foregoing description, it will be observed that when the device 43 is fitted into an opening 56, provided at the bottom of the tank 1, communication is thus established through the passages 38, 39 and 44 and the conduits 35 and 36 to the interior of the supply tank 1. The opening, of course, of the passages is controlled by the valve 37, which is first operated when a bottle 41 is positioned, as shown in Figure 3, to admit air from the top of the tank into the bottle through the member 43 and sealing device 42. When the pressure of gas has been equalized in the tank and in the bottle, the valve is actuated to close the communicating passage to the top of the tank through the pipe 35, and opens a passage through the opening 44 to the tube 45 whereby liquid is permitted to flow from the bottom of the tank to the bottle 41. The admission of liquid to the bottle 41 displaces the air therein and forces it into the member 43, the interior tube 46 of which provides a chamber for its reception. As a result the bottle may be completely filled with carbonated liquid from the tank to the exclusion of any air that may have been previously contained therein.

Although, no description of the general operation of the machine has been set forth,

it is believed that the construction of the various devices comprehended by my invention will be clear inasmuch as they are adapted to particular portions of the machine which have been shown in connection therewith. It is to be noted that I provide particularly efficient means for controlling the gas pressure maintained in the supply tank, and I have found that my improved means when set to operate at a bottling pressure produces a greatly improved product and greatly improves operating conditions in that any desired bottling pressure may be constantly maintained. Furthermore, the pressure which will provide a constant escape of air and undesirable gases may be readily determined thereby facilitating the operation of the machine, and improving the qualities of the beverage being bottled.

Particular attention should be given to the cylindrical member 43, which provides suitable passages for the inlet and escape of air to and from the bottle being filled, which also aids in improving the quality of the beverage, particularly when carbonated liquids are being employed. It is well known, of course, that it is desirable to exclude air from the liquid since this tends to give it a flat, sour taste, whereas the carbonated liquid improves its qualities and assists in maintaining it in proper condition. It should furthermore, be noted that the filling tube 45 is supported in such manner that its durability is insured, and if it should become broken after continued use, the disassembly of the member 43 affords ready means for removing the broken part and of its replacement.

Although I have shown and described, somewhat specifically, a plurality of devices adapted to be used in combination with a bottle filling machine, it is obvious that minor changes may be made in their construction and in their application without departing from the spirit or scope of the invention, and I desire, therefore, that no limitations shall be imposed except such as are indicated in the appended claims.

Having thus illustrated my invention and described the same in detail, what I claim as new and desire to secure by Letters-Patent is:—

1. In a bottle filling machine, the combination with a supply tank adapted to contain liquid and gases under pressure, of means for conducting liquid to bottles, said means including a conduit communicating with the supply tank, a sealing device, slidably mounted upon said conduit, means for securing said conduit to the machine including a cylinder, removable end closing members in said cylinder, said conduit secured to both of said end closing members, the cylinder being provided with an exteriorly threaded surface adapted to fit into a correspondingly

threaded opening provided in the machine.

2. In a bottle filling machine the combination with a supply tank adapted to contain liquid and gases under pressure, of a filling tube, a member mounted thereon formed of telescoping tubes said filling tube mounted in said member, said telescoping tubes providing a chamber about the filling tube, the upper end of the outer tube being secured directly to the tank, the filling tube being secured at the upper end thereof to the tank and secured to the outer tube at the lower end thereof, means for regulating a liquid level in the tank, and means for limiting fluid pressure in the tank.

3. That method of bottling carbonated beverages which consists first in feeding the carbonated beverages under pressure into an enclosed chamber, causing a constant escape of air from the upper part of said chamber and drawing liquid from the bottom of said chamber whereby the free air will escape from the liquid in the chamber, substantially as and for the purposes herein set forth.

4. That process of bottling a carbonated beverage which comprises partly filling an enclosed chamber with a carbonated beverage, introducing gas under pressure to the upper portion of the chamber; bringing the pressure to a predetermined point, causing the gas to constantly escape at said point, constantly maintaining the pressure of the gas at said point, conducting the beverage from the bottom of said chamber to bottles, simultaneously introducing into the chamber a sufficient quantity of the beverage to replace the amount drawn therefrom, whereby the amount of liquid within the chamber will be constantly the same and the pressure in the upper part of the chamber will be constantly maintained by gas escaping from the beverage within the chamber.

5. That process of bottling a carbonated beverage which comprises conducting a predetermined quantity of the beverage to an enclosed tank, constantly maintaining the same quantity of beverage within the tank, introducing gas under pressure to the upper portion of said tank, until a certain predetermined pressure is reached, causing a constant escape of gas from the upper portion of

the tank, constantly maintaining the pressure of the gas in the upper portion of the tank and conducting the beverage from the lower portion of the tank to bottles.

55

6. That method of bottling carbonated beverages which consists in first maintaining a body of carbonated liquid in an enclosed chamber, causing a continuous escape of air from the top of said chamber, withdrawing liquid from the bottom of said chamber into bottles, passing the displaced air from said bottles to the upper part of said chamber and venting same to the outside air along with the first mentioned air.

65

7. That method of bottling carbonated beverages which consists in first maintaining a body of carbonated liquid in an enclosed chamber, causing a continuous escape of air from the top of said chamber and withdrawing the carbonated liquid from the bottom of the chamber.

70

8. That method of bottling a carbonated liquid which consists in partly filling an enclosed space with the liquid, filling the upper part of the space with gas under pressure, causing gas to continuously escape from the upper part of said space, constantly replenishing the gas thus escaping, drawing the carbonated liquid from the bottom of said space and constantly replacing the amount of liquid withdrawn.

75

9. That method of bottling a carbonated liquid which consists in partly filling an enclosed space with the liquid, filling the upper part of the space with gas under pressure, causing gas to continuously escape from the upper part of said space and drawing the carbonated liquid from the bottom of said space.

80

10. That method of removing free air from a carbonated beverage which consists in partly filling an enclosed space with the liquid, filling the remainder of said space with gas under pressure; causing the gas to slowly and continuously escape from the upper part of said space, withdrawing liquid from the bottom of said space and constantly replacing the liquid withdrawn.

85

In testimony whereof I have hereunto set my hand.

SAMUEL GREENHOUSE.

100
